UNITED STATES PATENT OFFICE.

ALVIN C. GODDARD, OF NEW YORK, N. Y.

DOOR CONSTRUCTION.

Application filed October 25, 1922. Serial No. 596,859.

This invention relates to metal doors and has for an object to provide a construction wherein the bottom and top rails, together with the body of the door, may be set up and secured together before the stiles are placed in position.

Another object of the invention is to provide a metal door wherein the ornamental beading is arranged to overlap at its junction in such a manner as to present a neat joint and at the same time present sufficient metal to permit spot welding.

A further object is to provide a construction where each part is accessible for quick and secure assembly, allowing the use of welding machines for securing the ends of rails to the stile molds without the use of inside mandrels or other devices which hamper speed of production.

Another object of the invention is to provide a construction where every operation can be performed with practical tools that are easy of upkeep.

A further object is to provide a construction where the molding member acts as an ornament, also as an interlock between the stile and rail, and also as a splice plate under the joint between the end of the rail and stile member, giving ample surface for welding and eliminating special notching and extra splice plates.

A further object is to provide an improved joint and connection between intersecting moldings with which an extremely rigid and strong attachment between the intersecting moldings may be obtained.

A further object is to provide an improved construction for accomplishing the above objects, which will be exceptionally strong, rigid, durable and relatively inexpensive.

Various other objects and advantages will appear from the description of an embodiment of the invention and the novel features will be particularly pointed out hereinafter in claims.

In the accompanying drawings—

Figure 1 is a fragmentary plan view of one corner of a door as the same will appear when completed.

Figure 2 is a fragmentary sectional view through Figure 1 approximately on line 2—2.

Figure 3 is a sectional view through Figure 1 approximately on line 3—3.

Figure 4 is a view similar to Figure 1 but

showing the parts broken away for illustrating how the vertical molding or trimming strip extends into the rail and stile.

Figure 5 is a plan view of the vertical molding or trimming strip at the point engaged by the horizontal trimming strip, the same showing the slit and bent structure.

Figure 6 is a plan view of one end of the horizontal molding as it appears immediately before it is fitted against the molding shown in Figure 5.

Figure 7 is an enlarged sectional view taken approximately on line 7—7 of Figure 3.

Figure 8 is a view similar to Figure 7 but showing the entire molding.

Figure 9 is a fragmentary perspective view showing the interior arrangement of the vertical and horizontal moldings at their point of connection.

Figure 10 is a detail fragmentary sectional view through Figure 4 approximately on line 10—10.

Figure 11 is a perspective view showing the same corner illustrated in Figure 1 but illustrating the arrangement whereby the stile may be slid into place after the other parts have been secured together.

Figure 12 is a fragmentary perspective view of the vertical stile showing the slit and bent section illustrated in Figure 5.

Referring to the accompanying drawings by numeral, 15 is a panel formed with a central body of asbestos or other desired material and facing sheets of metal whereby the panel is of the fireproof type. This panel is designed to fit into the panel groove 16 of the vertical molding or trimming strip 17 and also of the horizontal molding or trimming strip 18. In the drawing, part of these two molding strips have been shown but it will be evident that for each panel there will be two vertical molding strips 17 and two horizontal molding strips 18 and that there may be as many panels in a given door as desired.

The moldings at their intersection may have a joint of the type known as a cope joint, which will allow one of the moldings to extend past the other. If a complete mitre joint were used, it would be impossible to have one of the moldings extend beyond the other. Where a part of the faces of the molding are curved or inclined, it is difficult to form a satisfactory complete cope joint. Preferably, in order to obtain the ad-

vantages of both types of joints and avoid the disadvantages of both, a combination joint has been utilized. This combination joint is part cope and part mitre, the mitre joint being utilized between the curved or inclined faces and the cope between the other surfaces. In making this joint, one of the moldings, such as 18, is shouldered at the angular or plain surfaces so as to fit properly 10 against the corresponding surfaces of the other molding, and is mitred or chamfered across the inclined or curved surfaces. The end of such a molding is shown in Fig. 6 in which two shouldered portions are 15 connected by a diagonal mitre edge 27. In the other molding strip which extends beyond the intersection, the curved or inclined surface is provided with a mitre slit 25, extending diagonally or obliquely of the molding 20 so as to form an edge 28 which is the component of the mitred edge 27 of the other molding strip. The portion 26 of the surface of the molding with the mitre slit, bordering upon the slit and where covered by 25 the curved or inclined surfaces of the intersecting strip is struck inwardly by an amount, at least equal to the thickness of the metal of which the molding is made, so as to allow the two intersecting inclined or curved 30 surfaces to abut edge to edge; the cut off mitred edge 27 of one molding strip abutting and fitting closely against the mitred edge 28 of the slit 25. The overlapping portions of the intersecting moldings may be spot welded 35 or otherwise secured together and form a strong and tight connection between the moldings, but where, as in a door, the moldings are along the edges of intersecting rails and stiles, the molding which passes under or through the other is preferably extended into the adjoining rail or stile and anchored thereto in any suitable manner such as by spot welding.

The particular shape in cross section, of 45 these moldings is illustrated in Figures 2, 3 and 12 wherein it will be seen that there is provided, not only longitudinally arranged grooves 16, but grooves 19 and 20 provided by having the edges turned over. These grooves are adapted to receive the in-turned flanges 21 and 22 of the various rails 23 and the respective stiles 24 whereby the rails may be slid into position and also the stiles slid into position.

50 After the moldings have been properly positioned and the panels 15 arranged therein, the various rails 23 are slid into position and then spot welded to the vertical molding 17 at any desired number of points 29; preferably several points between the molding 18 and the opposite edge of the rail. This arrangement leaves the grooved portions 19 and 20 of the molding 17 projecting beyond the rails 23 so that the respective stiles 24 55 may be slid into position, and if desired,

locked in position by one or more suitable spot welding connections 30. This completes the manufacture of the door unless top and bottom covering plates 31 are desired, which if desired, are slid into position from the 70 edge of the door and there held in position by friction or by spot welding. The spot welding of the plates 31 consists of only a few spots as there is no appreciable strain on this member. Preferably, the top and 75 bottom ends of the stiles are cut off straight while the bottom edges of the bottom rails and the top edges of the top rails are bent over so as to present flanges as indicated in Figures 2 and 11 for receiving the finishing 80 plate 31, said finishing plate, however, extending entirely across the bottom of the respective stiles to which it is spot welded in any desired manner. The stiles may be merely slid into place as above stated and 85 held by a single spot weld though preferably they are pressed together after correctly slid into position and then provided with a single spot weld 30 or if desired with a number of spot welds. In order to do this a mandrel 90 is forced longitudinally into the molding 17, said mandrel fitting said molding and then a press is used which presses down on top of the stile and in that way presses both the top and bottom flanges 20 and 21 at the same 95 time. It will be understood that the mandrel completely fills the molding 17 or at least extends from the top flange 22 to the bottom flange 21 as illustrated in Figure 3 so that the pressure of the top of the structure will be communicated to the bottom 100 in order that both edges of the stile may be rigidly pressed into position.

What I claim is:—

1. In a metal door, a vertical stile part 105 and a horizontal rail part meeting at an angle and in the same plane, a molding strip running along that edge of one of the parts against which the other part abuts and extending into and secured to said other part, 110 and a molding strip running along the edge of the said other part and intersecting the first named strip in a partial cope and partial mitre joint to form an angular continuation thereof.

2. In a metal door, a vertical stile part 115 and a horizontal rail part meeting at an angle and in the same plane, a molding strip running along that edge of one of the parts against which the other part abuts and extending into and secured to said other part, 120 and a molding strip running along the edge of the said other part and intersecting the first named strip in a partial cope and partial mitre joint, the portion of the face of 125 the first named strip along the mitre joint being struck inwardly to clear the overlapping portion of the second strip.

3. In a metal door, a vertical stile part 130 and a horizontal rail part meeting at an an-

- gle and in the same plane, a molding strip running along that edge of one of the parts against which the other part abuts and extending into and secured to said other part, 5 and a molding strip running along the edge of the said other part and intersecting the first named strip in a partial cope and partial mitre joint, the face of the first strip along the mitre joint being slit and the edge 10 bordering the slit and beneath the second named strip being struck inwardly to clear the overlapping portion of said second strip.
4. In a metal door of the character described, a vertical molding strip extending from near the top to near the bottom of the door provided with diagonal slits at spaced intervals, a horizontal molding strip formed with a diagonally arranged end fitting into 15 one of said slits, top and bottom rails overlapping the top and bottom ends of said vertical molding strip, said rails being spot welded to said molding strip, and a sliding stile arranged on said vertical molding 20 strip, said stile being capable of being placed in position after the top and bottom rails have been welded to said vertical molding.
5. In a metal door of the character described, a bottom rail, a horizontal molding 25 strip carried by said bottom rail formed with a chamfered end and a vertical molding strip formed with a diagonally arranged slot and the metal adjacent the slot pressed
- inwardly so that the chamfered end of the horizontal molding strip may fit against the slotted portion of the vertical molding strip with the outer surfaces flush, said vertical molding strip extending into said rail, said extending portion being spot welded to said rail.
6. In a metal door of the character described, a panel, a horizontal molding strip for said panel, a vertical molding strip for said panel extending beyond the horizontal molding strip and forming an end projection, a rail carried by said horizontal molding strip overlapping part of said projection, said vertical molding strip being provided with a stile guiding groove extending longitudinally thereof, and a stile slidably mounted in said groove, said stile being capable of connection with said extension after the same has been slid into correct position.
7. In a sheet metal construction, two sheet metal moldings intersecting in the same plane and at an angle to one another, the curved and inclined intersecting surfaces being mitred and the other surfaces having a cope joint, the portion of one of the mitred surfaces along the mitre and covered by the overlying corresponding surface of the other molding being depressed to allow of a flush fit of the mitred surfaces.

ALVIN C. GODDARD.
